(57) **CLAIM**

The ornamental design for a clothes hanger, as shown and described.

DESCRIPTION

FIG. 1 is a front, left, and perspective view of a clothes hanger, showing our new design.

FIG. 2 is a rear, right and perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view according to broken short dash-long dash circle 9 shown in FIG. 1.

The broken lines depict portions of the clothes hanger that form no part of the claimed design.

The short dash-long dash broken lines represent the boundaries of the partial enlarged view and form no part of the claimed design.
